(57) **CLAIM**

The ornamental design for a super tri-leveler, as shown and described.

DESCRIPTION

FIG. 1 is a top, back, right side perspective view of a super tri-leveler showing my new design;

FIG. 2 is a bottom, back, right side perspective view thereof;

FIG. 3 is a front elevational view thereof;

FIG. 4 is a back elevational thereof;

FIG. 5 is a right side elevational view thereof, the left side elevational view being a mirror image thereof;

FIG. 6 is a top plan view thereof; and,

FIG. 7 is a bottom plan view thereof.

The broken lines illustrate portions of the super tri-leveler that form no part of the claim.
